UNITED STATES PATENT OFFICE.

LEONARD SYKES AND JAMES H. NAVE, OF FORT WAYNE, INDIANA, ASSIGNEES TO
ANY LITE COMPANY, OF NORTH YAKIMA, WASHINGTON, A CORPORATION OF
WASHINGTON.

ELECTRIC-LIGHT REGULATOR.

1,198,970.

Specification of Letters Patent. Patented Sept. 19, 1916.

Application filed December 18, 1915. Serial No. 67,655.

To all whom it may concern:

Be it known that we, LEONARD SYKES, a subject of the King of Great Britain, and JAMES H. NAVE, a citizen of the United States, residing at Fort Wayne, in the county of Allen and State of Indiana, have invented certain new and useful Improvements in Electric-Light Regulators; and we do hereby declare the following to be a full, clear, and exact description of the invention, such as will enable others skilled in the art to which it appertains to make and use the same.

This invention relates to electric light regulators, and has for an object to provide improved means for increasing or decreasing resistance as the required or desired light may make this necessary.

A further object of the invention is to provide an improved light attachment having a resistance coil located therein connected at one end to the line, and with an improved swinging contact adapted to engage the coil with the swinging contact also in circuit.

A further object of the invention is to provide improved means for manually controlling the swinging contact.

Another object of the invention is to provide improved means for cutting a resistance into a circuit adapted for use in an electric light socket, an auxiliary socket or wall receptacle.

With these and other objects in view the invention consists in certain novel features of construction, combination and arrangement of parts as will be hereinafter more fully described and claimed.

In the drawings:—Figure 1 is a longitudinal diametrical sectional view through an auxiliary socket embodying the present invention. Fig. 2 is a transverse sectional view through the casing on the line 2—2 of Fig. 7, showing the top of one of the blocks with the screw plug of the socket removed. Fig. 3 is a transverse sectional view taken on line 3—3 of Fig. 1, with the resistance coil removed. Fig. 4 is a view in side elevation of the two porcelains clamping the resistance coil and showing the swinging contact in perspective. Fig. 5 is a perspective view of the swinging contact removed. Fig. 6 is a diagrammatic sectional view showing the engagement of the swinging contact with the resistance coil. Fig. 7 is a view in side

elevation of the auxiliary type of socket. Fig. 8 is a diametrical longitudinal sectional view of a socket embodying the present invention adapted to be attached directly to a conductor. Fig. 9 is a sectional view through the casing taken on line 9—9 of Fig. 8, showing the upper porcelain in plan as well as the swinging contact. Fig. 10 is a detail sectional view showing the means of forming electrical contact between the plug and the swinging arm in a type of socket shown at Fig. 1. Fig. 11 is a view in side elevation of the type of socket shown at Fig. 8. Fig. 12 is a view in section of a wall receptacle embodying the present invention. Fig. 13 is a sectional view of a wall receptacle embodying the present invention taken at right angles to Fig. 12. Fig. 14 is a perspective view of the base porcelain of the type employed at Figs. 12 and 13. Fig. 15 is a view in front elevation of a wall receptacle embodying the present invention showing the extended ends of the coil for manual actuation.

Like characters of reference designate corresponding parts throughout the several views.

The improved light regulator which forms the subject-matter of this application comprises a base porcelain shown at 20 in the type shown at Fig. 1, with a superposed porcelain 21 thereon. The base porcelain 20 is preferably provided with a central hub 22 with a squared portion 23 engaging in complementary sockets in the superposed porcelain 21.

The porcelain 20 is provided with a beveled or inclined annular portion 24 forming an annular space between the porcelains 20 and 21 diminishing in depth toward the center within which space is located a coil 25 of resistance wire. The resistance wire is of course insulated in the usual well-known manner with the insulation scraped from the upper surface of such wire as indicated at 26 in Fig. 6 immediately below the arcuate slot 27 in the porcelain 21, such slot being shown more particularly at Fig. 2. Pivoted at 28 to the porcelain 21 is a swinging contact 29 having a spring finger 30 bearing directly upon skinned surfaces of the resistance coil as shown at Fig. 6. The contact finger 30 is provided with a stamped indentation 31 as shown at Fig. 5 which produces upon the under or contact surface of

such finger a protuberance for engaging with the wire.

The porcelains 20 and 21 are embraced within a housing 32 which carries the usual 5 socket 33 which is in turn electrically connected with the resistance coil 25 by means of an extension of said coil passing through the opening 34 as shown at Fig. 3, and secured to the socket as shown at 35 in Fig. 6.

10 A further sleeve 36 embraces the casing 32 and the whole structure is secured together by means of a bolt 37 which extends downwardly through the plug porcelain 38, through the porcelains 21 and 20, and is provided at its lower end with the contact 39. The socket 33 is secured to the porcelain 20 by means of a bolt 40, and the whole device is ventilated by means of the openings 41 in the porcelain 20 and 42 in the porcelain 21, and the openings 43 and 44 in the casing.

15 The swinging contact member 29 is manipulated by means of cords 45 and 46 which pass through openings 47 and 48 respectively, and are attached to the swinging contact member 29 by being passed through the opening 49 therein and secured thereto in any approved manner as by the knot 51, and said cords are respectively upon the exterior of the casing provided with pendant 25 members 52 and 53. The metal sleeve 54 about the plug porcelain 38 is electrically connected with the swinging contact member 29 by a finger 55 formed integral therewith and engaging against the head of the 30 bolt at 28, as shown more particularly at Fig. 1. Means as the rib 56 provides a tongue and groove connection between the porcelain 21 and the porcelain 38 whereby the relation of the two porcelains is maintained to maintain the finger 55 in engagement with the pivot 28, while the porcelains 21 and 20 are maintained in non-rotatable 35 position by means of the squared member 23.

40 As shown at Figs. 8, 9 and 11, the socket 45 is intended to attach to the ordinary conductor 57, a bushing 58 being employed to engage the casing 59 in substantially the usual 50 and ordinary manner. The porcelains 20 and 21 are substantially the same as disclosed in Figs. 1 to 7 inclusive, but connection is made by substituting the porcelain block 60 for the block 56. To the block 60 a contact bracket 61 is secured connected with the bolt 37, and a second contact bracket 62 is provided with a finger 63 resting upon the pivot 28.

55 The inclosing structure differs from the inclosing structure of the device shown at Figs. 1 to 7 inclusive only in that the casing 64 is substituted for the sleeve 36 to engage the bushing 58. The manual cords 45 and 46 are brought out through openings 47 and 48 in the casing 64 and the openings 66 are 60 preferably placed higher up than the openings 44. A lip 67 is also preferably struck

in at 68 to bear on the porcelain 21 to properly position the parts.

To arrange the parts for use in a wall receptacle, the base porcelain shown at 68 is provided with ears 69 to secure the same to 70 the receptacle 70 as shown at Figs. 12 and 13. The porcelains 21 and 60 are connected the same as in the disclosure of Fig. 8, and the manual cords 45 and 46 run outwardly through bushings 71 and 72 respectively 75 formed in the receptacle cover 73, and the coil 25 is connected with the bolt 37 as shown at Fig. 12 indicated in dotted lines at 74. Whichever the construction, the coil 25 is in all instances surrounded by a band 80 or ring of insulating material 75 so that at the extreme outward limit of movement the contact finger 30 bears upon such insulating material to wholly break the circuit. The center of the annulus composed of the resistance coil 25 is also preferably composed of a ring 76 of little or no resistance upon which the contact finger 30 rests when the light is to be on at full voltage.

85 It is obvious therefore that as the contact finger is moved manually in its arc across the stripped surfaces of the resistance coil it first leaves the ring 76, offering but little resistance connected directly with the light, and moves to cut in increasing coils of resistance until adjacent the periphery the resistance has become so great as to practically extinguish the light when a further move onto the insulating material 75 serves to break the circuit entirely. It is obvious 90 therefore that in turning on a light by this contrivance the finger if first moved from the insulating material through the resistance decreasingly to full voltage whereby the current is turned on at the light gradually and avoiding thereby the shock of sudden impressing of the high voltage upon the filament of the lamp. This tends to 95 save the filament and increase the life of the lamp.

100 We claim:

1. The combination with an electrical conductor, of a pair of insulating blocks spaced apart by an interval increasing in width from the center, a contact ring located in the space nearest the center, a resistance coil filling the space and having one end attached to the ring, an insulating material located at the outer periphery of the space, a swinging contact member located upon one of the blocks and adapted for engagement with the ring and the resistance coil, and manual means for swinging the contact member upon a pivot.

110 2. The combination with an electric circuit, of a pair of insulating blocks spaced apart, a conductor ring located in the space and connected with one side of the circuit, a resistance coil located in the space and having one end connected with the ring, an 115 120 125 130

insulating material inclosing the resistance coil and located at the periphery of the block, and a swinging contact member electrically connected with the other side of the 5 circuit and adapted to progressively engage the resistance coil from the conductor ring upon one side to the insulating material upon the opposite side.

3. The combination with an open electric 10 circuit, of a housing embracing the terminals of the circuit, a pair of insulating blocks spaced apart located within the housing, a conductor ring located within the space adjacent the center and connected with one 15 of the terminals, a resistance coil located within the space and having one end con-

nected with the ring, a swinging contact member connected with the other terminal and having a finger in engagement with the resistance coil, an insulating material located upon the external periphery of the coil and in position to engage the finger, and flexible members connected with the swinging contact and extending outwardly through the casing. 20

In testimony whereof we affix our signatures in presence of two witnesses.

LEONARD SYKES,
JAMES H. NAVÉ.
